UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,132,166.

Specification of Letters Patent. Patented Mar. 16, 1915.

Application filed November 14, 1913. Serial No. 800,937.

To all whom it may concern:

Be it known that I, CORNELIUS B. CORCORAN, a citizen of the United States, residing in the borough of Bronx, in the county of 5 New York, city and State of New York, have invented certain new and useful Improvements in Type-Writing Machines, of which the following is a specification.

This invention relates to means in type-writing machines for releasing the platen from the control of the line-space wheel.

The object of the invention is to produce a simple, inexpensive and reliable device of this character, which will permit adjustment 15 of the platen with reference to the line-space wheel.

Loose upon the platen axle is a head which carries oppositely disposed dogs, each of which has a series of very fine teeth 20 which are normally in mesh with a fine ratchet or knurl provided upon the line-space wheel. The dogs have inwardly extending arms which are simultaneously engaged by a collar which is slid along the 25 platen axle by pressure upon a finger piece or abutment placed on the outward side of the hand wheel, which is usually fixed upon the end of the platen axle.

It will be seen that a very simple structure is attained, since a single member sliding along the platen axle engages a plurality of dogs to swing them out of engagement with the locking teeth of the ratchet wheel. The dogs may be so placed that 35 when the teeth on one dog fit in the locking teeth of the line-space wheel, the teeth on the other dog would be out of mesh, thus doubling the range of adjustment, and otherwise permitting twice as fine adjustment as in the case of a single dog.

The clutching mechanism is contained with a barrel that is preferably provided upon the line-space wheel; and by loosening a holding collar, the line-space wheel and 45 barrel may be slid along the platen axle, thus uncovering the clutching mechanism and giving access thereto for examination and cleaning. The barrel is closed by a simple device.

50 Other objects and advantages will herein-after appear.

In the accompanying drawings, Figure 1 is a perspective view of part of an Underwood paper carriage, to which my invention 55 is shown applied. Fig. 2 is a sectional view

showing the clutching device in its normal operative position, in which the line-space wheel is locked to the platen axle by means of the clutch dogs. Fig. 3 is a sectional view showing the clutch dogs disengaged 60 from the line-space wheel, to release the latter from the platen axle. Fig. 4 is a detail perspective of the parts comprising the clutching mechanism. Fig. 5 is a view of one of the clutch dogs, to show the teeth 65 provided on its nose, which engage the fine teeth on the side of the line-space wheel. Fig. 6 is a modified form of the clutch, in which one dog engages the fine teeth, while the other dog rests on the top of said teeth, 70 which arrangement provides for a finer adjustment of the line-space wheel.

The usual platen 1 is fixed upon an axle 2 journaled in the ends of a platen frame 3. Line-spacing is effected by lever 4, plunger 75 5, pawl 6 and line-space wheel 7, connected to the platen axle with a clutch. Dogs 8 are provided with fine teeth 9 on their noses 10 to engage fine teeth 11 on the line-space wheel 7, and are pivoted at 12 in a block or 80 yoke 13 fast to the platen axle. The platen may be released from the platen axle 2, by releasing or withdrawing the dogs from engagement with the line-space wheel teeth. This is effected by pushing a button 14, 85 which by means of long stems 15, passing through the recessed finger wheel 16, is connected to a loose collar 17 on the platen axle 2, and presses said collar against a sleeve 18, to thrust the latter against tails 18^a formed 90 on the dogs, and thereby rocks the latter to swing their noses 10 clear of the line-space wheel teeth.

The collar 17 is retracted by means of the springs 19, after pressure is removed from 95 the push button. As stated in the brief description of Fig. 6, the dogs may be so arranged that while one dog rests on the top of the cut teeth, the other is in engagement with said teeth. To effect this, the dogs 100 must be mounted so that one engages half a tooth in advance of or behind the other dog.

The clutch is normally kept closed by springs 19, which are seated in pockets 20 in the yoke 13, and bear against the tails 18^a 105 (also provided with pockets 20) of the dogs. To protect the clutch members, a shell or wall 21, on the line-space wheel 7, has a groove 22 in its inner surface, and is provided with openings 23, through which ears 110

24 of a cover 25 may enter said groove. By a slight subsequent rotation of the cover, the latter will be secured. To inspect or clean the clutch, the cover 25 is removed and then 5 by loosening the set screw 26 in the collar 27, the line-space wheel may be moved away from the dogs, exposing the entire mechanism.

Variations may be resorted to within the 10 scope of the invention, and portions of the improvements may be used without others.

Having thus described my invention, I claim:

1. In a typewriting machine in combination 15 an axle, a platen fixed thereon and provided with a finger wheel, a line-space wheel adapted to turn on said axle, a series of teeth cut on the outside face of the line-space wheel, a yoke fixed upon the axle, a 20 spring-pressed tailed dog pivoted in said yoke, adapted to engage said teeth, a sliding sleeve on the axle adapted to engage the tail of said dog to release the dog from engagement with the said teeth, a loose collar on 25 said sleeve, a stem connected to said collar and passing through the finger wheel at one side of the axle, and a push button mounted on said stem outside the finger wheel.

2. In a typewriting machine in combination 30 an axle, a platen fixed thereon and provided with a finger wheel, a line-space wheel adapted to turn on said axle, a series of teeth cut on the outside face of the line-space wheel, a yoke fixed upon the axle, a 35 multi-toothed spring-pressed tailed dogs pivoted in said yoke, adapted to engage said teeth, a sliding sleeve on the axle adapted to engage the tails of said dogs to release the dogs from engagement with the said teeth, a loose collar on 40 said sleeve, stems connected to said collar and passing through the finger wheel, and a push button connecting said

stems and adapted to move into the recess of said finger-wheel when pressure is applied to said button.

3. In a typewriting machine in combination 45 an axle, a platen fixed thereon and provided with a finger wheel, a line-space wheel adapted to turn on said axle, a series of teeth cut on the outside face of the line-space wheel, a yoke fixed upon the axle, a 50 spring-pressed multi-toothed dogs pivoted in said yoke, each provided with teeth adapted to fit the said series of teeth and spaced so that said engagement of one dog is half a tooth in advance of the engagement of the other dog, a sliding sleeve on the axle adapted to engage the tails of said dogs to release the dogs from engagement with the 55 said teeth, a loose collar on said sleeve, stems connected to said collar and passing through the finger wheel, and a push button connecting said stems and adapted to move into the recess of said finger wheel when pressure is applied to said button.

4. In combination with a platen fixed upon an axle, a line-space wheel loose on 60 said axle, a series of fine teeth on the side of said line-space wheel, a grooved casing formed on said line-space wheel, dogs pivoted in a yoke fixed on the axle within said casing, an adjustable collar on said axle engaging said line-space wheel to keep said line-space wheel within the range of said dogs, to permit the latter to engage the fine teeth on the line-space wheel to hold it to the axle under the protection of the casing, and a removable cover provided with ears 65 for engaging the groove in the casing.

CORNELIUS B. CORCORAN.
